CLAIM

The ornamental design for an expandable broadhead, as shown and described.

DESCRIPTION

FIG. 1 is a perspective view of an expandable broadhead in the closed position, showing my new design;
FIG. 2 is front view thereof;
FIG. 3 is a back view thereof;
FIG. 4 is a left view thereof;
FIG. 5 is a right view thereof;
FIG. 6 is a top view thereof;
FIG. 7 is a bottom view thereof;
FIG. 8 is an exploded perspective view thereof;
FIG. 9 is a perspective view of an expandable broadhead in the opened position;
FIG. 10 is a front view thereof;
FIG. 11 is a left view thereof;
FIG. 12 is a back view thereof;
FIG. 13 is a right view thereof;
FIG. 14 is a top view thereof;
FIG. 15 is a bottom view thereof; and,
FIG. 16 is an exploded perspective view thereof.
The dash-dot broke lines in the drawings depict projection lines and form no part of the claimed design.
